UNITED STATES PATENT OFFICE.

GEORGE SHELTON, OF PADUCAH, KENTUCKY.

DESIGN FOR A PUMP-FRAME.

47,251.

Specification for Design.

Patented Apr. 20, 1915.

Application filed September 25, 1914. Serial No. 863,562. Term of patent 14 years.

To all whom it may concern:

Be it known that I, GEORGE SHELTON, a citizen of the United States, residing at Paducah, in the county of McCracken and State of Kentucky, have invented a new, original, and ornamental Design for Pump-Frames, of which the following is a specification, reference being had to the accompanying drawing, forming a part thereof.

The figure is a perspective view of a pump frame, showing my new design.

I claim:

The ornamental design for a pump frame, as shown.

GEORGE SHELTON.

Witnesses:

W. H. RIFLY,
H. E. SHELTON.
